BUILDING CONSTRUCTION

Edmund H. Lunken, Hartsdale, and George A. Just, Scarsdale, N. Y.

Application January 24, 1935, Serial No. 3,242

7 Claims. (Cl. 72—115)

This invention relates to building constructions and particularly to means for clamping together a plurality of slabs, sheets or blocks of building material to provide a wall for a building.

5 It is an object of the invention to provide clamping means of the character described which may be used with materials of varying thicknesses and constructions; which will tightly clamp the materials together to produce substantially a 10 weatherproof connection; which is flexible and elastic to accommodate settlement, expansion and contraction; and which may be readily applied without the use of special tools or appliances.

Other objects will be in part obvious and in 15 part pointed out hereinafter.

Illustrative embodiments of the invention are shown in the accompanying drawing, in which:—

Figure 1 is a top plan view of the clamping members in separated position.

20 Fig. 2 is a side elevation of the same.

Fig. 3 is a top plan view of the clamping members in connected position.

Fig. 4 is a side elevation of the same.

25 Fig. 5 is similar to Fig. 3 but includes two blocks of building material clamped between the clamping members and showing the manner in which the flexible and elastic clamping member is flexed by the clamping action and tightly clamps the blocks.

30 Fig. 6 is a top plan view of a modified form of the clamping members in connected position.

Fig. 7 is similar to Fig. 6 but includes a flexible and elastic weather strip associated with one of the clamping members.

35 Fig. 8 is a top plan view of another modification of clamping members and a flexible and elastic weather strip.

40 As conducive to a better understanding of the invention it may be noted that heretofore considerable difficulty has been encountered in aligning and connecting slabs or blocks of building material to form a building wall. Devices heretofore employed for this purpose have been expensive and difficult to apply and have not been 45 adjustable for different thicknesses of slabs or blocks. The present invention is intended to eliminate the difficulties heretofore encountered.

45 Referring to Figs. 1 and 2, the clamping means of this invention consists of two separate clamping members designated respectively A and B, and which are adapted to cooperate and clamp between them two adjacent slabs or blocks of building material.

50 Member A which may be the structural steel framework of a building is T-shaped and con-

sists of a head 1 and stem 2. Passing through stem 2 adjacent its extremity are one or more pins 3 which may be made of solid metal or of tubing 5 burnished into place by the use of an expanding tool to enlarge the extremities of the pin for a purpose hereinafter described.

Member B preferably consists of a single sheet of flexible and elastic metal such as aluminum or steel bent to form two spaced legs 4 and a head 5, the extremities of which extend at an 10 oblique angle to the legs 4.

As shown in Fig. 2, legs 4 are provided with one or more slots 6 extending upwardly at an angle to the perpendicular. Legs 4 are spaced apart a sufficient distance to readily straddle stem 2 15 of member A, and slots 6 of member B are large enough in cross-section to readily slip over pins 3 of member A.

Referring to Fig. 4, members A and B are connected in clamping relationship by lowering the 20 slots 6 of member B over pins 3 of member A. The slanting angle of the slots 6 draws member B toward member A until sufficient clamping action is obtained. The enlarged extremities of pins 3 prevent spreading of legs 4 when pins 3 are 25 forced into slots 6.

In Fig. 5, members A and B are shown clamping between them two slabs or blocks of building material 7. To secure a firm clamping action the upper extremity of member B is preferably 30 struck with a hammer to force it downwardly and inwardly toward member A. The farther member B is driven downwardly the tighter the 35 clamping action. The flexibility of the head 5 of member B permits it to be distorted from the 40 shape shown in Fig. 3 to the shape shown in Fig. 5 when it contacts with and is forced against the slabs or blocks 7. The elasticity of the head 5 of the member B causes it when distorted to press 45 tightly against blocks 7 and this tight pressure because of the elasticity of the head will not be substantially reduced under settlement, expansion or contraction, and will provide at all times a tight weatherproof covering for the intersection between the blocks 7. The clamping members may be applied to seal vertical or horizontal 50 intersections between adjacent slabs or blocks and may be of sufficient length to seal a plurality of such intersections.

55 In a series of superimposed clamping members, the upper extremity of the topmost member A may be extended and provided with a series of holes 21 through one of which a bolt or pin 22 may be passed to contact the upper extremity 55

of the topmost member B and prevent upward displacement of the members B.

For certain purposes, the modified form of clamping means shown in Fig. 6 may be used 5 to advantage. In the construction there shown, the member B is also T-shaped, thus providing only one leg 4, and the head 5 extends at right angles to the leg 4 instead of at an oblique angle thereto. Such a construction does not, however, 10 provide the elastic tight construction which is produced by the construction shown in Figs. 1 to 5.

To provide a tight connection with the construction shown in Fig. 6, a flexible and elastic 15 weather strip 8 having inwardly projecting arms 9 may be slipped over the head 5 of member B, as shown in Fig. 7. Such a weather strip will provide the tight connection which may be desirable in certain building constructions.

20 In Fig. 8 is shown a modification of clamping means provided with an elastic weatherproof strip for producing a tight connection. As there shown, the member B consists of three members, namely, a head 10, a member 11 formed to provide two spaced legs 12, and an elastic weather strip 13 interposed between the head 10 and the member 11. The three parts just referred to may be welded together. The extremities of the weather strip 13 are bent to form an oblique 25 angle between each extremity and a leg 12, so that when the member B is forced downwardly and toward member A, the strip 13 contacting with a slab or block of building material will be flexed from its normal position toward head 10 and thereby increase the pressure of the strip 30 13 against the blocks or slabs clamped between members A and B.

It will be understood that the invention is not 40 to be limited to the specific embodiments shown for purposes of illustration as the inventive features may be variously embodied without departing from the invention. For example, the pins 3 may be carried by the member B and slots 6 formed in the stem 2 of member A. In this suggested construction, the slots 6 will, of course, extend downwardly in the member A instead of upwardly as they do in member B.

It will also be understood that all of the features of the invention need not be used conjointly 50 as they may be used to advantage in various combinations as defined by the sub-joined claims.

The expression V-shaped head as used in the claims is intended to include a head so formed that opposite side edges of the head will be the 55 first parts of the head to contact with the wall-forming material when the clamping member B is forced against the wall-forming material. Such a head formation may take the form of the broadened V-shape shown in Fig. 3 or may 60 take the form of a broadened U-shape. The expression V-shaped head is not intended to limit the invention to any particular angle or spacing between the legs of the V or the U.

The expression T beam as used in the claims 65 is intended to include any building framework construction having a base or head against which wall-forming material may be pressed and having a stem extending from the base or head and capable of supporting the clamping member B.

70 We claim:

1. Means for clamping wall-forming material to the framework of a building comprising, in combination with a T beam of the framework, a pin extending through the stem of the T beam 75 at substantially a right angle thereto, and a flex-

ible and elastic metal clamping member formed to provide an elongated V-shaped head and an elongated stem extending inwardly from or adjacent the apex of the head, the stem consisting of two spaced legs to straddle the stem of the T beam and the legs being provided with aligned slanting slots to receive the pin, whereby when the clamping member is forced down over the pin it will be drawn toward the T beam and against the wall-forming material and be flexed out of its normal plane and will clamp the sections of wall-forming material between the clamping member and the T beam with an elastic clamping pressure to accommodate settling movement, expansion or contraction of the wall-forming material. 10 15

2. Means for clamping sections of wall-forming material to the framework of a building comprising in combination with a T beam of the framework, a pin extending from the stem of the T beam, and a flexible and elastic metal clamping member formed to provide an elongated V-shaped head and an elongated stem extending inwardly from or adjacent the apex of the head, the stem being provided with a slanting slot to receive the pin extending from the stem of the T beam, whereby when the clamping member is forced down over the pin it will be drawn toward the T beam and against the wall-forming material and be flexed out of its normal plane and will clamp the sections of wall-forming material between the clamping member and the T beam with an elastic clamping pressure to accommodate settling movement, expansion or contraction of the wall-forming material. 20 25 30 35

3. Means for clamping sections of wall-forming material to the framework of a building comprising, in combination with a T beam of the framework, a pin extending from the stem of the T beam, and a clamping member formed of an integral sheet of flexible and elastic metal to provide an elongated V-shaped head and an elongated stem extending inwardly from or adjacent the apex of the head, the stem consisting of the extremities of the sheet of metal spaced apart 40 45 to straddle the stem of the T beam and being provided with aligned slots to receive the pin, whereby when the clamping member is forced down over the pin its head will be drawn toward the T beam and flexed out of its normal plane 50 and will clamp the sections of wall-forming material between the clamping member and the T beam with an elastic clamping pressure to accommodate settling movement, expansion or contraction of the wall-forming material. 55

4. Clamping means of the character described, including a clamping member having an elongated V-shaped head of flexible and elastic metal, whereby when pressed against the material to be clamped the V-shaped head will be flexed out of its normal shape, and means cooperating with the clamping member to retain the head in its flexed condition, whereby an elastic pressure will be exerted against the clamped material to accommodate settling movement, expansion or contraction of the material. 60 65

5. Clamping means of the character described, including a clamping member having an elongated V-shaped head of flexible and elastic metal whereby when pressed against the material to be clamped the V-shaped head will be flexed out of its normal shape, and a pair of spaced legs of flexible and elastic metal extending from spaced points adjacent the apex of the head and provided with means cooperating with the clamp- 70 75

ing member for retaining the head in its flexed condition against the material to be clamped, whereby an elastic pressure will be exerted against the clamped material to accommodate settling movement, expansion or contraction of the material.

6. Clamping means of the character described, including a clamping member having an elongated V-shaped head of flexible and elastic metal, portions of which are formed to provide a double wall whereby when pressed against the material to be clamped the head including the double wall portions thereof will be flexed out of normal shape, and means cooperating with the clamping member to retain the head including the double wall portions thereof in flexed condition, whereby an elastic pressure will be exerted

against the clamped material to accommodate settling movement, expansion or contraction of the material.

7. Means to clamp wall-forming material to the framework of a building comprising a clamping member having associated therewith a V-shaped clamping portion of resilient metal whereby when pressed against the material the V-shaped portion will be flexed out of its normal shape, and means cooperating with the clamping member to retain the V-shaped portion in its flexed condition whereby a continuing pressure will be exerted against the clamped material to accommodate settling movement, expansion or contraction of the material.
